UNITED STATES PATENT OFFICE.

DAVID CAUGHEY, OF NEW YORK, N. Y.

INTERNAL-COMBUSTION-MOTOR PISTON.

Application filed December 20, 1921. Serial No. 523,723.

To all whom it may concern:

Be it known that I, DAVID CAUGHEY, a subject of the King of Great Britain, and a resident of the city of New York, borough of 5 Manhattan, in the county and State of New York, have invented a new and Improved Internal - Combustion - Motor Piston, of which the following is a full, clear, and exact description.

10 The present invention relates to new and useful improvements in internal combustion motor pistons.

It is one of the objects of the invention to provide a piston in which the use of 15 split packing rings may be dispensed with.

It is a further object of the invention to construct the piston so that a single packing ring of a continuous type is employed.

It is a further object of the invention to 20 construct the piston so that it is provided with a plurality of heat-dissipating elements.

It is a further object of the invention to construct the piston so that the heat dissipating elements may be removed if desired. 25

With the above and other objects in view, reference is had to the accompanying drawings, in which—

Figure 1 is a view in elevation of a piston 30 constructed in accordance with the present invention;

Fig. 2 is a horizontal sectional view of the piston, with a portion thereof broken away;

Fig. 3 is a vertical central sectional view 35 of the piston.

Referring more particularly to the drawings, the piston is designated by the reference character 5 and the reference character 40 6 designates the skirt thereof, which skirt is provided with the usual wrist pin openings 7. The body of the piston is cut away as indicated by the reference character 8 to provide a shoulder 9 and mounted on said 45 shoulder 9 and surrounding the piston is a ring 10. The ring 10 is of the continuous type and is positioned on the piston in the following manner:

The ring 10 is heated to extreme temperature 50 at which it is expanded to its limit of expansion, and is then placed over the cut-away portion 8 of the piston 5 and forced home into engagement with the shoulder 9 thereof. This ring 10 then contracts and is 55 retained in position upon the piston by said contraction or shrinking. Owing to the ex-

treme temperature to which the ring is heated in placing it upon the piston, it is apparent that the coefficient of expansion of said ring under the influence of heat is 60 reduced, and that a piston construction formed in accordance with this principle will expand to a lesser degree than one constructed in the ordinary manner.

Extending from the upper face of the 65 piston is a projection 15 and said projection is preferably circular in cross sectional form. Carried by the upper face of the piston is a plurality of radially corrugated heat-dissipating plates 16, and interposed with respect to these plates 16 are flat plates 17, there being one flat plate 17 placed between each two corrugated plates 16. The diameter of the corrugated plates 16 and the flat plates 17 is less than the diameter of the 70 ring 10 as indicated by the reference character 18 in Figs. 1 and 3. These plates are secured in position on the piston 5 by means of a top plate 19, and said top plate is secured in position by means of a screw 20 or 75 the like, engaging an internally threaded recess 21 in the extension 15.

The device functions in the following manner:

When the piston is in the motor cylinder 80 and the expansion takes place, the force of the explosion is downwardly upon the plate 19 giving the necessary impetus to the piston. As the gases expand, they pass around the edge of the plate 19 and into the 85 space between the edges of the plates 16 and 17, where they rush inwardly through the spaces indicated by the reference character 30 and formed by the corrugations of the corrugated plates 16, and the heat is thus 90 trapped within these spaces. By trapping the heat within the spaces it is obvious that the same is held in close contact with the cylindrical walls, thus transferring the heat partly to the greater area of the heat dissipating device and partly to the cylinder 95 walls and thence to the water in the jackets.

From the foregoing it is apparent that the present invention provides a piston for use in internal combustion motors in which the 100 necessity of using split rings, is eliminated, and, at the same time, the construction of the piston permits of the use of a single continuous ring for providing a gas-tight joint between the piston and the walls of the cylinder in which the piston operates. Furthermore, the present invention provides means 110

for dissipating the heat of the charge and thus reduces the heat which the piston attains during working conditions.

I claim:

- 5 1. In a piston for motors, a main body portion, a continuous ring carried thereby, and a plurality of radially corrugated heat-dissipating elements removably carried by said piston and superimposed with respect to said ring.
- 10 2. In combination with an internal combustion motor piston, a plurality of radially corrugated heat dissipating elements removably carried thereby, the diameter of said heat-dissipating elements being less than the diameter of the piston.
- 15 3. In an internal combustion motor piston, a body portion, a continuous packing ring carried thereby, and heat-dissipating elements carried above the body portion of the piston and superimposed with respect to said packing ring, substantially as described.
- 20 4. In an internal combustion motor piston, a packing ring carried thereby, and heat-dissipating elements of smaller diameter than the piston and removably carried thereby, said heat dissipating elements arranged in juxtaposition to said packing ring.
- 25 5. In an internal combustion motor piston,

a plurality of heat-dissipating devices, said heat-dissipating devices comprising a plurality of radially corrugated plates, flat plates interposed with respect to said corrugated plates, and means for securing said corrugated plates and flat plates rigidly together to form a unitary structure.

6. In an internal combustion motor piston, a plurality of heat-dissipating devices, said heat-dissipating devices comprising a plurality of radially corrugated plates, flat plates interposed with respect to said corrugated plates, and means for securing said corrugated plates and flat plates rigidly together to form a unitary structure, said securing means comprising a removable piston head.

7. In an internal combustion motor piston, a plurality of heat-dissipating devices, said heat-dissipating devices comprising a plurality of radially corrugated plates, flat plates interposed with respect to said corrugated plates, and means for securing said corrugated plates and flat plates rigidly together to form a unitary structure, said means comprising a plate and means for securing said plate to the piston, said plate forming the head of said piston.

DAVID CAUGHEY.
